UNITED STATES PATENT OFFICE.

GILLES HOLST, EKKO OOSTERHUIS, AND JOHANNES BRUIJNES, OF EINDHOVEN, NETHERLANDS, ASSIGNEES TO NAAMLOOZE VENNOOTSCHAP PHILIPS' GLOEILAMPEN-FABRIEKEN, OF EINDHOVEN, NETHERLANDS.

ELECTRICAL-DISCHARGE DEVICE.

Application filed November 4, 1921. Serial No. 512,890.

The invention relates to electrical discharge devices with independent discharge having a gaseous filling and particularly relates to discharge devices for rectifying alternating currents in which the discharge has the character of a glow discharge.

An independent discharge is an electric discharge which is started simply by supplying a suitable alternating or direct current-tension to the electrodes without requiring cathode incandescence or any auxiliary device, to liberate electrons or ions in the path of the discharge, such as characterize X-rays or ultraviolet-rays.

The object of the invention is to provide a new type of the device described which is simple and rugged in its construction.

Contrary to the opinion expressed in current literature, it has been found that in a discharge tube the disruptive voltage is not independent of the material of the electrodes, especially of the material of the cathode. When the distance between the electrodes is not too great, or the gas pressure is relatively small, the disruptive voltage for any given gas, principally depends on the material of the electrodes.

According to this invention use is made of this property in constructing a rectifier.

This in its simplest form consists of a discharge tube, filled with a so called rare gas, such as argon and is provided with two electrodes of different materials, e. g., magnesium and a relatively refractory material such as iron. The disruptive voltage now is considerably smaller, when the magnesium constitutes the cathode than when the iron forms the cathode. Thus it will be clear, that when this rectifier tube is connected to a suitable source of alternating voltage, current can only pass when the magnesium forms the cathode, so that a rectifying effect is obtained. An insulating screen is placed between the electrodes to preserve the cathode against destructive disintegration.

In the accompanying drawing a discharge device is diagrammatically illustrated suitable for rectifying current and provided

with electrodes of different material according to the invention.

One embodiment of the invention, as shown in the drawing, consists of a sealed vessel 1 consisting of glass or the like, a cathode 2 of magnesium and an anode 3 of iron.

Cathode and anode are connected to current-conveying conductors 6 and 7 sealed into stems 8 and 9. In order to prevent disintegration of cathode to anode and of anode to cathode which would cause the rectifying properties to be reduced a shield 4 may be provided between the electrodes. This shield may be supported by any suitable means, e. g., by two stems 5. The shield may consist of mica or any other suitable insulating material. The gaseous filling of the tube may consist of argon or another rare gas; and the device may be adapted for use with a voltage of 110 volts, for instance, the electric discharge in the tube having the character of a glow-discharge.

The device described and illustrated may be considered as a preferable embodiment of the invention, but it will be obvious to persons skilled in the art that various modifications will be possible within the scope of the following claims.

What we claim is.

1. An electrical glow-discharge device with independent discharge adapted for rectifying alternating currents, comprising an envelope, a rare gas therein, two electrodes of different material so chosen that the disruptive tension is different in one direction than in the other and a shield of insulating material interposed between said electrodes.

2. An electrical glow-discharge device with independent discharge adapted for rectifying alternating currents, comprising an envelope, a rare gas therein, two electrodes, one of said electrodes consisting of magnesium, the other of a relatively refractory material and a shield of insulating material interposed between said electrodes.

3. An electrical discharge device adapted for rectifying alternating currents, compris-

ing the combination of an envelope, a filling of rare gas therein, two electrodes of different material within said envelope and a shield of insulating material interposed between said electrodes.

4. An electrical discharge device adapted for rectifying alternating currents, comprising the combination of an envelope, a filling of rare gas therein, a cathode of magnesium

and an anode of iron and a shield of mica ¹⁰ interposed between said cathode and said anode.

In testimony whereof we affix our signatures.
